(57) **CLAIM**

I claim the ornamental design for a stage for a motor vehicle door, as shown.

DESCRIPTION

FIG. 1 is a top view of the stage for a motor vehicle door showing the new design; and,

FIG. 2 is a perspective view of the stage for a motor vehicle door as shown in FIG. 1, in accordance with the present invention.

1 Claim, 2 Drawing SheetsFIG. 1

FIG. 2
